Arthur Ross, Detroit, Mich., assignor to General
Motors Corporation, Detroit, Mich., a corporation of Delaware

Application November 23, 1949, Serial No. 6,216

Term of patent 7 years

(Cl. D14—6)

To all whom it may concern:

Be it known that I, Arthur Ross, a citizen of the United States being a resident of Detroit, State of Michigan, have invented a new, original, and ornamental Design for an Automobile Emblem Plate or Similar Article, of which the following is a specification, reference being made to the accompanying drawing, forming a part thereof.

In the drawing:

Figure 1 is a plan view showing an automobile emblem plate or similar article having a design in accordance with my invention.

Figures 4, 5 and 6 are sectional views taken substantially on lines 4—4, 5—5 and 6—6, respectively, of Figure 1.

I claim:

The ornamental design for an automobile emblem plate or similar article, substantially as shown.

ARTHUR ROSS.
